SLOTTED SCARFING BURNER

Joseph F. Kiernan, Dunellen, N.J., assignor to Air Reduction Company, Incorporated, New York, N.Y., a corporation of New York

Filed June 28, 1966, Ser. No. 561,199

14 Claims. (Cl. 239—556)

ABSTRACT OF THE DISCLOSURE

Cutting oxygen is supplied through several passages through the back face of the burner into a header that extends the width of the burner. On both sides of the points of entry of the supply passages into the header the header opens forwardly into jet passages elongated in the direction of the width of the burner, the jet passages jointly forming a nearly continuous but subdivided jet. The jet passages open into a rectangular slot cut into the front face of the burner, the height of the slot being a little greater than the height of the jet passage. Beginning a short distance from the forward opening of the jet passages and extending substantially to the front face of the burner, are upper and lower inserts extending the entire width of the burner and restricting the oxygen to a relatively thin sheet between them. The faces of the inserts toward the jets are shaped to promote turbulence in the sheet of oxygen. The combination of features promotes a uniform distribution of oxygen flow across the entire width of the burner. Preheat orifices in the face of the burner extend in a row above and a row below the oxygen slot.

This invention relates to scarfing burners which are used for directing oxygen against a surface of a billet, slab, or other workpiece for the purpose of removing defective surface metal before the workpiece is rolled to final form.

In order to remove cracks, and other surface perfections while the steel is on the rolling mill line, it is a practice to remove the entire surface from the workpiece by means of oxygen jets directed against the heated surface at a low angle of attack. When a row of individual jets is disposed transversely of the workpiece, there is more metal removed along the center axis of each jet than along the sides, and the jets must be of sufficient size and close enough together to remove the necessary depth of metal at the region where the jets are least effective. This results in the removal of more metal than necessary at the regions where the jets are more effective, and the scarfed surface has a wavy transverse contour, whereas it would be ideal to have a flat surface since the waves represent excessive metal removal and resulting waste.

It is an object of this invention to provide an improved scarfing burner which removes surface metal from a workpiece with less variation, transversely of the workpiece, in the depth of metal removed and with a resulting smoother surface after the scarfing operation.

Another object is to provide a scarfing burner with a plurality of oxygen outlets in the face of a burner which is constructed so as to produce turbulence of the oxygen and a resulting more even distribution of the oxygen supply transversely of the direction of relative movement of the burner and the workpiece.

The preferred embodiment of the invention has a row of oxygen jet passages, each of which is elongated in the direction in which the row extends, and with the outlets of the jet passages closely spaced from one another. The face of the burner is recessed so that there is a substantial distance from the discharge face of the oxygen jets to the workpiece and this gives the oxygen time

2

to distribute more evenly across the length of the burner and the transverse width of the workpiece.

Another object of the invention is to provide a scarfing burner of the character indicated with the burner constructed of separate parts assembled in such a way as to simplify the manufacture and reduce the cost of the burner. One feature relates to the use of inserts in the recessed face of the burner with the inserts extending part way into the path of the oxygen streams and with faces of the inserts that are at an acute angle to the direction of flow of the oxygen streams for producing a uniform, sheet-like stream of oxygen.

Other objects, features and advantages of the invention will appear or be pointed out as the description proceeds.

In the drawing, forming a part hereof, in which like reference characters indicate corresponding parts in all the views:

FIGURE 1 is a fragmentary front view of a scarfing burner made in accordance with this invention;

FIGURE 2 is a sectional view taken on the line 2—2 of FIGURE 1;

FIGURES 3 and 4 are sectional views taken on the lines 3—3 and 4—4, respectively, of FIGURE 2;

FIGURE 5 is a view similar to FIGURE 1 but showing the back of the burner;

FIGURE 6 is an enlarged, fragmentary, sectional view of a portion of the construction shown in FIGURE 2; and

FIGURE 7 is a diagrammatic view showing the way in which the burner of this invention is used for removing surface metal from a workpiece.

FIGURES 1 and 2 show a scarfing burner 10 having a body portion 11 with an upstanding lug 12 for connecting the burner to a supporting manifold block. The lug 12 has openings 14 through which fastening means, such as bolts, extend for securing the burner to the support.

The burner has a front face 18 which includes a forwardly-extended upper face portion 20 with an undercut shoulder 22 at its lower end, and a lower face portion 24. Through upper and lower faces pre-heat orifices 26 and 28 are drilled.

The upper pre-heat orifices 26 are located in a row extending lengthwise of the burner face 18, and these orifices 26 open into a header passage 30 in the body portion 11. Fuel gas is supplied to the header passage 30 through a passage 32, shown in FIGURE 2; and there are a plurality of such passages 32 at spaced locations along the length of the header passage 30 so as to obtain more uniform pressure and flow distribution lengthwise of the passage 30.

In the construction illustrated in the drawing, there are two passages 32, as shown in FIGURE 5, but it will be understood that there can be more than two passages and that by providing more supply passages 32, the cross section of the header passage 30 can be made smaller, without having objectionable pressure drops in the portion of the passage 30 between the supply passages 32.

The lower pre-heat orifices 28 open into a header passage 38 which is supplied with fuel gas through a plurality of supply passages 40, in the same manner as the passages 32 supply the header passage 30, already described.

The front face 18 is recessed between the rows of pre-heat orifices 26 and 28 by a continuous channel 44 running lengthwise of the burner face and extending for substantially the full length of the burner. The portion of the burner body through which the channel 44 extends, is of composite construction, as will be explained in connection with FIGURE 6, but for the present, a de-

scription of the composite construction is not necessary to a description of the operation of the burner.

A bottom or inner wall 46 of the channel 44 has a plurality of oxygen jets 48 opening through it and these oxygen jets communicate with an oxygen header passage 50. Each of the oxygen jet orifices 48 is elongated in the direction of the length of the burner 10. These orifices 48 may be of oval shape, but they are preferably constructed with semi-circular ends and parallel top and bottom walls, as best shown in FIGURE 4. The orifices 48 are spaced closely together; the spacing shown in the drawing being approximately equal to, or slightly greater than, the height of each orifice. The term "height" is used herein to designate the dimension of the elongated orifice at right angles to the elongated dimension of the orifice and in a plane normal to the longitudinal axis of the orifice. The length of each oxygen orifice 48, in proportion to its height, is not critical but better results are obtained by having the elongated dimension of each orifice many times greater than the height and in the construction shown, the elongated dimension is approximately nine times the height. A length-to-height ratio for the outlets of the orifices 48 between six and twelve, is desirable.

In order to obtain the highly uniform oxygen flow from the different oxygen jet orifices 48, it is important to maintain the oxygen pressure in the header passage 50 as uniform as possible. To attain this result without making the header passage 50 excessively large in cross section, a plurality of oxygen supply passages 54 are provided through the back of the burner, communicating with the header passage 50. FIGURE 5 shows four oxygen supply passages 54. These passages are of large cross section and preferably of a cross section substantially approaching that of the header passage 50.

In the preferred construction, one of the oxygen supply passages 54 opens into the header passage 50 between every two oxygen jet passages 48. This is advantageous because the tendency is for gas velocities to reach a maximum at the center of a jet discharged from an orifice; and by bringing the oxygen into the header passage 50, at the sides of the jet orifices 48, such pressure drop as does occur in the header passage 50 compensates the tendency of jet streams to have a higher velocity midway between the sides of the stream. The oxygen supply passages 54 are drilled into the body portion 11 of the burner at an angle, as shown in FIGURE 2, so that the flow of the oxygen has to change its direction before reaching any part of the jet orifices 48, and this also tends to obtain more uniform flow of oxygen through the oxygen jet orifices.

An important feature of this invention is the production of turbulence of the oxygen as it flows from the jet orifices 48 through the channel 44 for final discharge from the channel 44 and into contact with the surface of a workpiece. This turbulence is produced by having inserts 60 and 62 located in the channel 44. Each of the inserts 60 and 62 extends for the full length of the channel; that is, from one side of the burner to the other. The insert 60 is against the upper wall of the channel 44 and the insert 62 is against the lower wall of the channel. The open area of the channel 44, between the inserts 60 and 62, is of course, much less than the original area of the channel, and the height of this open area is preferably somewhat less than the height of the oxygen jet orifices 48. Thus, the inserts 60 and 62 extend part way into and interfere with the path of the oxygen streams as they discharge from the orifices 48. The disturbance caused by this extension of the inserts into the path of the oxygen streams produces the turbulence of the oxygen which tends to distribute the oxygen and oxygen pressure more uniformly across the full length of the burner as the oxygen flows from the jet orifices 48 to the discharge end of the channel 44.

In the construction illustrated in FIGURE 2, the insert 60 has an end face 64, and the insert 62 has an end face 66, at the end of the insert which confronts the discharge ends of the orifices 48. These end faces 64 and 66 are at an angle to the direction of the oxygen flow. This angle can be a right angle, but it is preferable to have it an acute angle; that is, to have the ends of the inserts 60 and 62 tapered at a steep angle. The angle is not critical, but best results are obtained by having it approximately 45° or more when the angle is measured between the sloping face of the insert 60 or 62 and the longitudinal axis of the oxygen jet orifice 48.

It is not essential but preferable that the open space between the inserts 60 and 62 be of less height than the oxygen jet orifices 48. Because of the fact that the parts of the faces 64 and 66 which contact with the oxygen streams to produce the turbulence are spaced some distance from the wall 46 through which the jet orifices 48 open, there is some expansion of the cross section of the oxygen jets before they strike the corners of the inserts where the walls 64 and 66 meet the parallel confronting faces of the inserts. It will be evident, therefore, that even though the spacing between the inserts 60 and 62 is as great as the height of the orifices 48, or slightly greater, the abutment surfaces provided by the end walls 64 and 66 are still in the path of the oxygen jets which have somewhat greater height than the outlets of the orifices 48 by the time they contact with these abutment surfaces of the inserts, as already explained.

In order to be most effective in producing turbulence and resulting mixing of the oxygen from the different jet orifices 48, the abutment faces 64 and 66 should make a sharp corner where they merge with the confronting faces of the inserts 60 and 62; that is, the merger should not be along a fair curve such as is used in nozzles for the purpose of preventing turbulent flow.

FIGURE 6 shows a detail of the construction of the burner. For more convenient manufacture, the channel 44 is made substantially greater in height than are the oxygen jet orifices 48, and the inserts 60 and 62 are then placed in the channel 44 as a convenient way of providing abutment faces extending part way into the path of the oxygen streams for producing turbulence. This is a practical and economical construction, but within the broader aspects of the invention, it is sufficient that the face of the burner be recessed, as is provided by the channel 44; that the oxygen jet orifices open through the recessed portion of the face; and that some abutment surfaces be provided in the recess, near the end of the recess into which the oxygen jet orifices open, regardless of whether these abutment surfaces are end faces of an insert or are part of a one-piece shoulder in the recess.

In the construction shown in the drawing, and especially in FIGURE 6, the inserts 60 and 62 are held in the channel 44 by lips 72 and 74 attached to an upper forward portion 76 and a lower forward portion 78, respectively, of the body portion 11 of the burner. These forward portions 76 and 78 are secured to the rearward part 90 of the body portion by any suitable fastening means, such as silver brazing or screws 92. The upper and lower faces 20, 24 and inserts 60, 62 being removable are easily replaced when worn or eroded. Thus the entire burner need not be discarded when these parts become worn.

Further to facilitate the manufacture of the body portion 11, the header passage 30 is made with a continuous slot 94 extending through the front surface of the rearward part 90. The upper pre-heat jet orifices 26 are drilled through the upper forward portion 76 in position to communicate with the slot 94. In similar manner, the header passage 38 is constructed with a slot 96 extending for its full length and opening through the front face of the rearward part 90 of the burner body and the lower pre-heat jet orifices 28 are drilled through the lower forward portion 78 in position to communicate with the slot 96.

FIGURE 6 also shows a feature of the preferred con-

struction in which a median plane 98, of the channel 44, extends at an angle to the plane of the face of the mid portion 24 of the burner. This angle is indicated by the intersection of the median plane 98 with a normal 100 to the plane of the mid portion 24 of the burner face.

The overhang construction, which is indicated by reference numbers 20 and 22 is only required to mechanically anchor pre-heat flames such as natural gas, propane etc. The overhang could be eliminated when acetylene is used as the fuel gas. No anchoring means is required on the lower face for any type of fuel.

The face of the burner has a lower portion 102 extending rearwardly at a sharp angle for facilitating the inclining of the burner to direct the oxygen and pre-heat jets downward at an acute angle to a work piece 104, as shown in FIGURE 7.

The preferred embodiment of the invention has been illustrated and described, but changes and modifications can be made and some features can be used in different combinations without departing from the invention as defined in the claims.

What is claimed is:

1. A scarfing burner comprising a body having a face with a row or orifices, said orifices being elongated in the direction in which the row extends, means for supplying oxygen to said orifices, the face of the burner being recessed in front of the row of oxygen orifices by a continuous slot extending in the same direction as said row of oxygen orifices, and the height of the open area at the downstream end of the slot being less than the corresponding height of the elongated oxygen orifices.

2. The scarfing burner described in claim 1 characterized by at least one other row of orifices, said other row of orifices extending in a direction generally parallel to the direction of extent of the row of oxygen orifices and at a location close to the downstream end of the recess in the face for supplying pre-heating flames for a scarfing operation.

3. The scarfing burner described in claim 1 characterized by the slot having a height substantially greater than the height of the oxygen orifices in a direction normal to the direction of the elongated extent of the oxygen orifices, but the open area of the slot being reduced along at least one inside surface thereof by an insert which obstructs part of the cross section of the slot and which leaves an open area of the slot with its height less than said corresponding height of the elongated oxygen orifices.

4. The scarfing burner described in claim 3 characterized by the end of the insert nearest to the oxygen orifices having a corner extending into the path of oxygen streams discharged from the orifices for producing turbulence and mixing of the oxygen streams from the different orifices as said streams are discharged through the slot.

5. The scarfing burner described in claim 4 characterized by inserts in both the top and bottom of the slot reducing the height of the open area of said slot.

6. The scarfing burner described in claim 5 characterized by each of the inserts having a corner at its end which is nearest to the oxygen orifices, the corner being spaced from said orifices and extending into the path of oxygen streams discharged from the orifices for producing

turbulence and increasing mixing of the oxygen streams from the different orifices as said streams are discharged through the slot.

5 7. A slotted scarfing burner comprising a burner body with a series of elongated oxygen supply passageways separate from one another, a continuous slot in the burner body and into which the oxygen supply passageways discharge, and inserts in the slot tapered for a short length at the upstream ends thereof for compressing and uniformly distributing the flow of oxygen across the slot.

8. The scarfing burner described in claim 7 characterized by the passageways being in a row lengthwise of the slot, and the elongation of each passageway being in the direction in which the row extends.

9. The scarfing burner described in claim 8 characterized by a header passage in the burner body for supplying oxygen to a plurality of the oxygen passageways.

10. The scarfing burner described in claim 9 characterized by a plurality of oxygen inlet passages opening into the header passage at locations spaced lengthwise of the header passage, means for supplying oxygen at substantially the same pressure to the different oxygen inlet passages to maintain substantially equal pressure of oxygen at all of the oxygen supply passageways.

11. The scarfing burner described in claim 10 characterized by the oxygen inlet passages opening into the header passage at locations between the successive oxygen supply passageways.

12. The scarfing burner described in claim 7 characterized by other jet orifices located in a row extending generally parallel to the slot and opening through a face of the burner near the discharge end of the slot for directing pre-heating jets against a surface to be scarfed and against the scarfing oxygen stream during operation.

13. The scarfing burner described in claim 7 characterized by the burner body being a composite construction and having face portions secured thereto with lips that extend across the downstream ends of the inserts to retain the inserts in the slot.

14. The scarfing burner described in claim 13 characterized by a header passage in the burner body above the slot, another header passage in the burner body below the slot, the header passages above and below the slot opening through a portion of the burner body with continuous openings that are covered by said face portions of the burner, and each of the face portions having a row of orifices extending therethrough and communicating with said continuous openings for supplying pre-heating jets to a work piece during a scarfing operation.
